UNITED STATES PATENT OFFICE

BERT F. CALLENDER, OF WICHITA, KANSAS

CONTAINER FOR MATCHES AND FRAGMENTS THEREOF

Application filed June 23, 1930. Serial No. 463,117.

My invention relates to a container for matches and fragments thereof.

The object of my invention is to provide a container that will receive a match box in one compartment and fragment of matches in another compartment.

A further object of my invention is to provide a container having two compartments, one as a storage for matches and having a lid, the other compartment as a storage for ignited matches and having a slotted lid that is funneled through which the fragments will pass and the lids for each compartment to close by gravity.

A still further object of my invention is to provide a spacing means in the container to separate the match box from the compartment.

A still further object of my invention is to provide a container, inexpensive to construct and the same to be pendently supported and will seat on a shelf or the like.

These and other objects will be hereinafter more fully explained reference being had to the accompanying drawings forming a part of this specification and in which like characters apply to like parts in the different views.

Referring to the drawings:

Fig. 1 is a front view of the container.

Fig. 2 is a side view thereof.

Fig. 3 is a plan view, parts removed for convenience of illustration.

Fig. 4 is a vertical section through the container.

My invention herein set forth consists of an L-shaped housing having a compartment 1 adapted to receive a match box 2 loosely engaging therein so that the same may be removed when empty and replaced with a full box of matches. The said compartment is equipped with a lid 3 pivotally connected at its inner corners by a stud 4 trunnion in aperture respectively. The pivot point of the said lid being in close proximity to the upper front wall 5 of the vertical compartment hereinafter described and stopped by detents 4' as means to insure the closing of the lid by gravity, when it is open to obtain matches that are stored there beneath, note

that the lid has a liberal projection over the side walls as shown at A in Figs. 1, 2, and 4, by which means the lid is easily raised by contacting the same with the fingers at the front and end portions.

In Figs. 3 and 4 is shown a pair of corrugations 6, the lower extremity of which protrude toward the match box, while the upper end thereof diminishes on the partition wall B, by which means the said match box is spaced from the partition wall and being so arranged that excess heat created within the adjacent compartment will be insulated from the matches contained in the box, should the same be placed with their ignitable heads thereto.

Vertically and rearwardly positioned to the match box storage compartment is a second compartment 7 functioning as a receptor for ignited or burnt matches, the upper end of the last said compartment has a lid 8 hingedly arranged and adapted to swing as shown by dotted lines C, the said lid being pivoted by a stud 9 at each of the rear corners thereof, and the said lid concentrically funneled as at 10, the said lid will close by gravity when opened at its full extremity.

At the frustum of the said funneled portion is an elongated slot 11, by which means should a match or fragmentary portion thereof be thrown on the lid it will readily pass through the slot into the compartment as a storage means therefor. It will be understood that the said slot is of sufficient size, to allow a standard make of match to pass through freely and should the match be burning it will be smothered out after its deposit in the compartment as the walls of said compartment are solid and the slotted opening is not sufficient in size to afford ample air for combustion, otherwise the said lid will close the upper end of the compartment snugly by the ends thereof fitting closely to the side wall that extends upward as at D, and the front portion has a lip 12 extending downward as shown in Figs. 1, 2, and 4.

Upwardly extending from the compartment 7, is the portion of the back as shown at E, the contour of which is merely for ornamentation and the design thereof may be

varied. Near each end of the extended portion is an aperture having a slot radially extending upward therefrom. The said aperture functioning as an entrance for the head of a nail or tack and when the container is dropped downward the neck portion of the said nail or tack will engage in their respective slots, by which means disengagement thereof will be impossible without raising the container.

One important feature of the lid 3 is that when the said lid is raised and a match withdrawn and lighted, it will immediately close and avoid the possibility of entering the un-ignited matches. As a means to insure the fragment of the consumed match, the lid 8, is funneled as previously described, consequently, the said match particle is easily guided through the slot.

While I have shown a container of sufficient width to receive a match box longitudinally therein, I do not wish to be so confined to such, as the container may be varied in width to receive matches independent of the box, or other forms may be adhered to and such other modifications may be made as lie within the scope of the appended claims.

Having fully described my invention, what I claim as new and desire to secure by Letters Patent is:—

1. In a container for matches and fragments thereof, a container having a compartment to receive a box of matches and a lid hingedly connected as closing means therefor, a plurality of corrugations on the back of the container and protruding inward and diverging downward as means to space a match box from the back thereof; a compartment extending upward and rearwardly positioned to the first said compartment as storage means for ignited matches; a lid hingedly arranged to close the upper end of the last said compartment, the lid having a lip turned downward at the outer edge thereof, and being funneled concentrically, the frustum end of the funnel being slotted for the purpose specified.

2. In a container for matches and fragments thereof, a container of the class described, comprising an elongated vertically positioned compartment with a funneled and slotted lid hingedly engaging on the upper end thereof, and a compartment outwardly extending and adjacent to the lower end thereof and being divided therefrom by a partition; the last said compartment having a lid hingedly connected and adjacent to the first said compartment; a pair of corrugations protruding into the second said compartment and slantingly positioned, substantially as shown and for the purpose specified.

3. In a container for matches and fragments thereof, a container of the class described, the combination of, a fragmentary match storage compartment, and a match

box storage compartment, the top of the last said compartment positioned below the top of the first said compartment, a pair of corrugations protruding into the second said compartment and converging upward, and as a spacing means for a match box from the partition, a straight lid for the second said compartment and a funneled and slotted lid for the first said compartment, by which means match fragments are guided into the first said compartment, all as and for the purpose specified.

4. In a container for matches and fragments thereof, a container having a compartment to receive a box of matches and a lid hingedly connected as closing means therefor, means to space a match box from the back of the container; a compartment extending upward and rearwardly positioned to the first said compartment as storage means for ignited matches; a lid hingedly arranged to close the upper end of the last said compartment, the lid having a lip turned downward at the outer edge thereof, and being funneled concentrically, the frustum end of the funnel being slotted for the purpose specified.

In testimony whereof I affix my signature.
